Inventor
Edward Hanff,

by *Edward Hanff*

UNITED STATES PATENT OFFICE.

EDWARD HANFF, OF LIVERPOOL, ENGLAND.

SHOVEL.

1,411,570.

Specification of Letters Patent.

Patented Apr. 4, 1922.

Application filed January 14, 1920. Serial No. 351,455.

To all whom it may concern:

Be it known, that I, EDWARD HANFF, a subject of the King of England, residing at 55 Rocky Lane, Anfield, Liverpool, in the 5 county of Lancaster, England, late of 71 Hatherley Street, Princes Park, Liverpool, in the county of Lancaster, England, engineer, have invented certain new and useful Improvement in Shovels, of which the 10 following is a specification.

This invention relates to spades, shovels, trowels, scoops, and the like, and has for its object to enhance their longevity.

As now commonly constructed, the front 15 of a spade, shovel, trowel, scoop, and the like—particularly a shovel of the type used in households—frequently becomes broken during use.

According to the present invention, the 20 front portion of the blade of the tool is thickened, either during the process of manufacture or formation thereof, or by means of a metal piece welded on to the underside of the blade proper, so as to be 25 integral and solid therewith.

Preferably, such "thickening" commencing at the front or edge, increases into wedge like or taper formation and then decreases until it merges into the normal thickness of 30 the blade, this wedge-like or tapering portion is, in effect, added to the underface of the blade, so that the upper face thereof is plain, or as usual.

If sides are formed out of a blade, the 35 thickened front portion, when bent, strengthens the sides.

I will further describe my invention with the aid of the accompanying sheet of explanatory drawings which illustrate 40 its application to a domestic shovel.

Fig. 1 is a rear view of the shovel.

Fig. 2 is a side elevation, and

Fig. 3 a cross section, taken as on line A A Fig. 1.

a generally designates a metal shovel the 45 front portion of the blade being thickened at *b* in the course of manufacture, such thickening, commencing from the front or edge of the shovel, increases into wedge-like formation and then decreases until it 50 merges into the normal thickness of the blade: said wedge-like or tapering portion being, in effect, added to the underside of the shovel, so that the upper face thereof is flat, as usual. Said thickened front portion also forms portions *c*¹ of the upstanding sides *c*.

Having now described my invention, what I claim as new and desire to secure by Letters Patent is:—

A shovel having a blade provided with outstanding side walls and the underside of the front portion of said blade provided with an integral thickened portion commencing from the front edge of the blade 65 and increasing into wedge like formation to provide a long beveled wall and then decreasing to form a short beveled wall adjoining the blade, the thickened portion extending transversely of the blade and on 70 to the side walls thereof.

In testimony whereof I affix my signature in the presence of two witnesses.

EDWARD HANFF.

Witnesses:

JOHN H. WALKER,
EMILY BURNETT.
